Specification of Letters Patent. Patented July 5, 1921.

Application filed August 14, 1919. Serial No. 317,394.

To all whom it may concern:

Be it known that I, SAMUEL E. ADAIR, a resident of New York, in the county of New York and State of New York, have 5 invented a new and useful Improvement in Amplifiers, of which the following is a specification.

The invention relates to an amplifier for electrical currents of all kinds, either varying 10 or continuous.

The object of the invention is to provide an amplifier, employing a tri-electrode device, which is capable of being worked in successive stages of amplification, and which 15 is free from oscillation disturbances, which result in producing what is known as a "howl", and also free from interference with the normal operation of the device due to the production of a negative charge on 20 the grid.

In the accompanying drawings Figure 1 is a diagram showing a simple form of the amplifier connected to a radio signal receiving antenna for amplifying the signal impulses and which will explain the principle 25 of the invention, and Fig. 2 is a similar diagram showing a number of the amplifiers connected in series to produce successive stages of amplification.

30 The invention utilizes amplifiers of the tri-electrode type, such as the well known vacuum tubes containing three electrodes, to wit, a plate electrode, a heated electrode or filament, and an interposed grid electrode.

35 Usually these electrodes are contained in a vacuum tube, such as in the well known "audion", but more recently tri-electrode devices of this kind capable of being operated in open air have been produced. This 40 invention can utilize either of said forms of tri-electrode devices.

In practically all prior amplifiers employing vacuum tubes or similar tri-electrode devices and which are worked in successive 45 stages of amplification, the coupling is effected by inductive methods, by using transformers either air cored or iron, or condensers employing either radio or audio frequencies and sometimes both; or by the 50 conductive method by using auto transformers; or by the resistance method. In the two last named types grid condensers are employed to prevent the positive potential of the plate battery from affecting the grid.

55 All of the above described methods are

objectionable because they employ in their circuits either inductance or capacity, and sometimes both, in which energy can be stored, which stored energy causes the circuit to have an oscillatory period of its own, which results in setting up these oscillations with the resulting interfering sound spoken of in the art as a "howl". Furthermore, when grid condensers are used, strong signals produce an excessive negative charge 60 on the grid, which seriously interferes with the normal operation of the tri-electrode device, commonly spoken of as "paralyzing" the tube. Efforts have been made to overcome this paralyzing effect by placing resistance leaks between the grid and the filament, but this seriously affects the sensitivity of the amplification in the case of weak signals. Another undesirable characteristic which is always present in all of 65 the above mentioned types of vacuum tube amplifiers is that they have a natural period as a whole, which requires that a particular adjustment be made for any particular frequency of alternating current in 70 order to secure the most satisfactory results. This results in additional complication and requires greater skill in order to secure satisfactory operation of the amplifiers. Another objection is that all the 75 aforementioned types of amplifiers depend on a changing or varying current or in other words the coupling is ineffective unless the current to be amplified is varying or changing.

90 The principal object of the present invention is to overcome the above objections in the use of vacuum tubes or other tri-electrode devices of the same character. Generally stated the invention consists in connecting such tri-electrode device in one branch of a Wheatstone bridge. A simple diagram illustrating this is shown in Fig. 1, in which is diagrammatically shown a typical form of Wheatstone bridge and a 100 typical form of a vacuum tube of the tri-electrode type. As here shown the reference letters A, B, X and Y illustrate the usual resistance branches of a typical Wheatstone bridge, with an indicator I connected 105 to the junction of the branches A-X and B-Y respectively, and with the source of current, to wit, a battery E, connected with its positive pole to the juncture of the branches X-Y and its negative pole to the 110

juncture of the branches A—B. The tri-electrode device is inserted in the X branch of the bridge, with the plate P connected to the positive side of the circuit and the filament F connected to the negative side thereof, said filament being provided with the usual heating battery H. The circuit O, carrying the impulses or electric currents to be amplified, is connected to the grid G, which, as usual in devices of this kind, is interposed between the plate and the filament. This circuit O has its opposite side connected to the juncture of the branches A and X of the Wheatstone bridge, and is shown as provided with a tuning condenser C and has inserted in it the secondary S of an oscillation transformer, the primary Q of which is shown as connected in a typical radio receiving circuit comprising the antenna T connected to the ground at U, and including the variable tuning inductance V. This particular connection is intended to illustrate merely one use of the amplifier. As is well known in the art when there is no potential upon the grid G, such as when no signal impulses are being received, the circuit from the plate to the filament has a definite and constant resistance so that if the other elements of the Wheatstone bridge, consisting of the elements A, B, X and Y, are balanced against this resistance through the tri-electrode device, a condition exists in which there is no difference in potential between the points at which the galvanometer I (or other indicator) is ordinarily connected, that is, at the juncture of the resistance branches Y and B, and A and X respectively. If now a potential is applied between the grid G and the filament F of the tri-electrode device, such as by the arrival of incoming signal impulses, the resistance of the path of conduction from the plate to the filament within the tube will be changed, and this results in a proportional difference in potential across the galvanometer or other indicator I, which difference in potential will be maintained as long as the potential is applied to the grid G. To secure the best arrangement the relative values of the several resistances will, of course, be selected with regard to the resistance of the tri-electrode device employed, as is well known in the art.

To secure a further amplification by means of the device described, an arrangement will be employed in which several Wheatstone bridges are connected in stages, one embodiment being shown in Fig. 2. Here each individual amplifying unit is the same as that shown in Fig. 1, a common heating battery being employed for the filament of all of the tri-electrode devices, with a variable resistance R in each filament circuit to control the degree of heating thereof. The galvanometer connection g of each bridge is

carried to the grid and filament of the next succeeding tri-electrode device, with the galvanometer connections of the last bridge of the series connected respectively to the grid G' and filament F' of another tri-electrode device, and with a telephone T' and local source E' connected to the plate P' and filament F' of said final tri-electrode device.

By this arrangement the proportional difference in potential produced in the first bridge, by the effect of the incoming signal impulses on the grid of the first tri-electrode device, is carried over to the grid of the second tri-electrode device, thereby causing a proportional difference in potential across the second bridge which is greater than the difference of potential across the first bridge, due to the energy added by the bridge-batteries in circuit. This difference in potential is in turn carried to the grid of the third tri-electrode device, and so on throughout the series. As a consequence an amplification of the received electrical impulses or electric current is effected in each bridge.

This Wheatstone bridge arrangement has shown excellent amplification in either the single or the multiple stage connection. The arrangement produces a stable condition which is easily controlled and is free from the usual disturbing effects. It has been found impossible with the described arrangement to cause any internal "howl" characteristic of other tri-electrode amplifiers coupled in the manner heretofore employed.

The potential of the grid of any of the tri-electrode devices, except the first, can be made either negative or positive, by either raising or lowering the filament current of the preceding tri-electrode device by adjustment of the resistance device R. This results in raising or lowering the direct current resistance of that particular tri-electrode device, thus unbalancing the bridge and causing a corresponding change in potential across the grid and filament of the succeeding tri-electrode device.

Certain resistance elements employed by me in the bridge arrangements of amplifiers had approximately 48,000 ohms resistance each. These were of the type known to the trade as "Lavite resistance units". They had a substantially negligible inductance, approximately 40 centimeters, and a capacity too small to be readily measured.

I claim:

1. Apparatus for amplifying electrical currents, comprising a Wheatstone bridge having a tri-electrode device connected by its plate and filament electrodes in one of the branches of said bridge, with the circuit carrying the current to be amplified connected between the grid and filament, and an indicator connected across said bridge.
2. Apparatus for amplifying electrical

currents, comprising a Wheatstone bridge, a tri-electrode device connected by its plate and filament in one branch of said bridge and having its grid and filament connected to the circuit carrying the current to be amplified, another Wheatstone bridge having a tri-electrode device connected by its plate and filament in one branch thereof and having its grid and filament connected across the preceding bridge, and an indicating device connected across the last bridge of the series.

5

10

15

3. Apparatus for amplifying electrical currents, comprising, in combination, a series of Wheatstone bridges each having a tri-electrode device connected by its plate and filament in one branch of the bridge, the grid and filament of the first tri-electrode device being connected to the circuit carrying the current to be amplified, the grid and filament of each succeeding tri-electrode device connected across the preceding bridge, and a translating or indicating device connected to the plate and filament of the last tri-electrode device of the series.
